Attorneys.

UNITED STATES PATENT OFFICE.

DAVID T. ROSENFIELD, OF CHICAGO, ILLINOIS, ASSIGNEE TO GENERAL AMERICAN TANK CAR CORPORATION, OF CHICAGO, ILLINOIS, A CORPORATION OF WEST VIRGINIA.

CAR UNDERFRAME.

Application filed October 10, 1924. Serial No. 742,830.

My improvement relates more particularly to body-bolster construction of under frames especially for tank cars, and my objects, generally stated, are to provide a construction which will be more economical to build than structures as hitherto provided; more easily and economically repaired; and shall be sufficiently strong to resist the stresses imposed upon it in use, especially where it forms a part of a tank car, such stresses comprising the stresses due to static or dead loads, the stresses produced by the car striking a curve, the indirect buffing and pulling transverse stresses produced by draft-gears under static loads on the body bolster members, and stresses produced by side-sway when the car is in motion.

Referring to the accompanying drawings:—

Figure 1 is a cross sectional view of a tank car embodying my invention, my improved body bolster construction being shown in elevation and a portion of the tank being broken away. Figure 2 is a similar view, with certain parts omitted, of a modification of the structure shown in Fig. 1. Figure 3 is a broken plan view of the structure shown in Fig. 1 with the tank and certain of the saddle-blocks, forming a part of the structure, removed. Figure 4 is a partial plan section taken at the irregular line 4—4 on Fig. 1 and viewed in the direction of the arrows, with portions of the spacer shown in section; and Figure 5, a broken elevational view taken at the line 5 on Fig. 1 and viewed in the direction of the arrow.

Referring to the construction illustrated in Figs. 1, 3, 4 and 5, the under frame of the car is formed of a center sill comprising two parallel, spaced-apart, channel girders 10, the upper and lower flange portions 11 and 12 of which extend outwardly, as shown, whereby the channel portions of the sill, represented at 13, toe outwardly. The girders 10 are connected together at their upper edges by a cover-plate 14 which overlies the flanges 11 throughout the length of the sill and is secured thereto by rivets 15. The girders 10 are also connected together, in the plane of each body bolster portion of the structure, by a center-brace member 16 secured to the girders by rivets 17; and extending across the underside of the sill and

across the member 16, at each body bolster, is a center-plate member 18 which is secured to the girders 10 by rivets 19 and to the member 16 by rivets 20.

Each body bolster portion of the car comprises two members 21, which are preferably cast steel members, which extend cross-wise to the sill and outwardly therefrom in opposite directions. The members 21 are of the same construction, each being so shaped as to be fitted at its inner end in the adjacent channel 13, as shown. Each member 21 is formed with a central web-portion 22 which may be apertured as represented at 23 and 24, to reduce its weight, and a marginally-disposed flange-portion 25 extending throughout the marginal edge of the member 21 and at both sides of the web-portion 22, the marginal edges of the openings 23 and 24 being provided with narrow flanges, as represented at 26. The members 21 are secured to the center sill by the rivets 15, 17 and 19, and by rivets 27, and additional connection between the members 21 and the center sill structure is provided by the provision of a plate 28 which extends cross-wise of the center sill and across the plate 14 to a position in which its opposite ends overlap the upper surfaces of the members 21, this plate being secured to the center sill structure by the rivets 15 and rivets 29 and 30, and to the members 21 by rivets 31 and 32.

The body bolster constructions described, in the particular illustrated construction, form saddles for supporting the tank, represented at 33, there being provided between the members 21 and the tank 33, a series of filler, or saddle, blocks 34 of any suitable material, as for example wood, such as are commonly provided.

The upper surfaces of the bolster members 21 are shown of concave form to conform generally to the curvature of the tank, though it will be understood that under certain conditions the upper surfaces of the members 21 may be varied, as desired, in some cases being made straight.

Each bolster member 21 is provided, adjacent its outer end, with depending pressed steel body side bearings 35, secured thereto by the rivets represented at 36, and at its outer extremity with an outwardly project-

ing lug 37 cast integrally with the member 21, and of general channel shape in cross section as shown in Fig. 5. The lugs 37 form supports for running-board-supporting members 38 and tank bands 139. The running-board-supporting members 38 are of channel form as shown in Fig. 5 and are telescoped on the lugs 37 to which they are secured by the rivets 39 and 40, the running-boards, represented at 140, being supported on the outer ends of the members 38. The ends of the tank bands 139, a pair of which is provided for the tank at each bolster portion, extend downwardly through holes 41 in the lugs 37 and are provided at their lower, protruding, threaded ends with nuts 42 for drawing the bands about the tank. Each member 21 is also shown as formed with a push-pole pocket 43 integral therewith, and at a point closely adjacent its inner end with a lug 44 at the opening 24 for receiving a U-bolt 45 provided for the purpose of clamping the air-line brake-pipe (not shown) in place.

23 One of the main purposes in devising the structure of this application, was to avoid the necessity of providing a connecting member, separate from the main body bolster forming portions, for directly connecting 30 these portions across their lower portions, either with each other or with the center sill, and this is accomplished by the construction shown in which the members 21 are so shaped and proportioned and so combined 35 with the center sill structure that they will resist the stresses to which the car is sub-

jectected in use without requiring such a cross connecting member.

The structure shown in Fig. 2 involves a modification of the connections between the members 21 and the center sill structure. In this case, instead of providing a plate, such as the plate 28 of Fig. 1, which extends continuously across the sill, two plates, represented at 45 are provided at opposite sides of the sill, these plates overlapping the members 21 and the corresponding edge portions of the center sill, as shown, and being secured to the members 21 by the rivets 31 and 32 and to the upper flange portions of the 50 girders 10 by the rivets 15, as in the case of the structure shown in Fig. 1, each plate 45 being connected with the cover plate portion 14 by staggered rows of rivets 46 and 47.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

A car underframe comprising a center sill structure, bolster-forming members carried by, and extending outwardly, from said center sill, one of said members containing an aperture therethrough for a brakeline pipe, a lug integral with said last referred to member and a clamping device carried by said lug and located at said aperture.

DAVID T. ROSENFIELD.
